(57) **CLAIM**

The ornamental design for an LED light-fixture module, as shown and described.

DESCRIPTION

FIG. 1 is a perspective view from above of the an LED light-fixture module;

FIG. 2 is a perspective view from below of the LED light-fixture module of FIG. 1, the details of the underside of the module being shown in phantom lines;

FIG. 3 is a right-side elevation of the LED light-fixture module of FIG. 1, the left-side elevation view being a mirror image thereof;

FIG. 4 is a bottom plan view of the LED light-fixture module of FIG. 1, the details of the underside of the fixture being shown in phantom lines;

FIG. 5 is a top plan view of the LED light-fixture module of FIG. 1; and,

FIG. 6 is a front elevation of the LED light-fixture module of FIG. 1, the rear elevation view being a mirror image thereof. The phantom lines are provided for illustrative purposes only and form no part of the claimed design.
